DOOR CHECK

Rex C. Jacobs, Detroit, Mich.

Application July 29, 1935, Serial No. 33,637

4 Claims. (Cl. 16—85)

This invention relates to door checks of the type shown in my co-pending applications Serial No. 23,352, filed May 25, 1935, and Serial No. 33,636 filed July 29, 1935.

The primary object of the present invention is to provide a door check suitable for use in combination with automobile doors, the check being designed to provide a cushioning action whereby the swinging movement of a door may be stopped without setting up stresses and strains in the door, the hinges or the parts of the automobile body supporting the door. In providing a check embodying cushioning characteristics it has been found that repeated opening and closing of the door results in the metal becoming fatigued due primarily to the fact that the cushioning part of the check is repeatedly strained beyond its elastic limit. Therefore, it is another object of the invention to provide a door check with cushioning means which avoids a fatigue condition being set up in the metal of the check and thus to increase the useful life of such checks.

With the above and other ends in view the invention is more fully disclosed with reference to the accompanying drawing, in which—

Figure 1 is a cross section illustrating the check in combination with a door;

Fig. 2 is a similar section illustrating the checking action, and

Fig. 3 is an elevation of the device.

Like characters of reference are employed throughout to designate corresponding parts.

The numeral 1 designates a door of sheet metal construction having its end wall 2 provided with an opening 3. Secured to the inner surface of the wall 3 is a socket 4, the rear wall of the socket being inclined as at 5 and provided with an aperture 6. A door jamb 7 has its end wall 8 provided with a pair of spaced apart lugs 9 supporting a pin 10, one of the lugs 9 being shown in the drawing.

The door check comprises a flat strip of metal bent to provide a loop 11 through which the pin 10 extends. Extending outwardly from the loop 11 and through the aperture 6 is a bowed run 12 which terminates at the shoulder 13. The shoulder 13 merges into a flat run 14 at the end of which is formed an arcuate part 15, the terminal 50 of the blank extending tangential to the curvature of the arcuate part 15 as indicated at 16.

A flat metal strip is welded or otherwise secured at 17 to the run 12 and has a straight run 18 diverging outwardly from the run 12. The run 55 18 terminates at a shoulder 19 and a flat run 20

extends from the shoulder 19 past the terminal 16.

The runs 12 and 18 are normally spaced apart a distance greater than the width of the aperture 6 so that when the door is moved, from the position shown in Figure 1 to that shown in Figure 2, the runs 12 and 18 must be compressed by the side walls of the aperture in order that they may be drawn through the same. This sets up a frictional condition which tends to retard movement 10 of the door after it passes a certain stage in its movement.

When the door is fully opened as shown in Figure 2 the run 20 presses against one side wall of the aperture 6 and functions to hold the end of 15 the run 12 against the opposite side wall of the aperture. The shoulder 13 is thus held against the inclined wall 5 to prevent the run 12 from being entirely drawn through the aperture. The shoulder 19 will act to prevent movement of the 20 door from its open to its closed position but due to the flexibility of the run 18 the shoulder 19 may be moved through the aperture 6 upon application of manual pressure on the door.

When the shoulder 13 initially engages the wall 25 5 the run 12 will be in a bowed condition and this bowed condition provides tensional resiliency which results in the cushioning action.

Although a specific embodiment of the invention has been illustrated and described it will be 30 understood that various changes may be made within the scope of the appended claims without departing from the spirit of the invention, and such changes are contemplated.

What I claim is:—

1. A door check comprising a spring metal blank bent to provide a pin retaining means, tensionally resilient means extending outwardly from said retaining means and having an abutment at its outer end, laterally resilient means united with 40 said abutment, and a laterally yieldable strip connected at one end to said tensionally resilient means and having its other end adapted for engagement with said laterally resilient means.

2. A door check comprising a spring metal blank 45 bent to provide a pin retaining means, tensionally resilient means extending outwardly from said retaining means and having an abutment at its outer end, laterally resilient means united with said abutment, a laterally yieldable strip connected at one end to said tensionally resilient means and having its other end adapted for engagement with said laterally resilient means, and an abutment on said laterally yieldable strip.

3. A door check comprising a spring metal strip 55

bent to provide a pin retaining loop at one end, a bowed run extending outwardly from said loop, a shoulder at the outer end of said run, said shoulder merging into a spring portion formed with its terminal extending at an angle relative to the plane of said run, and a flexible strip having one of its ends attached to said run and its other end extending beyond and adjacent to the end of said terminal.

10 4. A door check comprising a spring metal strip bent to provide a pin retaining loop at one end,

a bowed run extending outwardly from said loop, a shoulder at the outer end of said run, said shoulder merging into a spring portion formed with its terminal extending at an angle relative to the plane of said run, a flexible strip having one of its ends attached to said run and its other end extending beyond and adjacent to the end of said terminal, and a shoulder on said flexible strip.
